UNITED STATES PATENT OFFICE

2,299,063

PIPE CUTTING APPARATUS

Jacob G. Heim, San Gabriel, Calif.

Application July 29, 1941, Serial No. 404,450

17 Claims. (Cl. 164—0.6)

My invention relates to apparatus for cutting pipe, and, since it finds particular utility in its application to the cutting of drill pipe in place in an oil well, objects and advantages of the invention pertinent to such application and embodiments of my invention well adapted for such use are described herein, it being understood that my invention is not limited to such application or use.

One of the objects of my invention is to provide apparatus adapted for cutting pipe in a well, which apparatus is capable of insertion and operation within a very small clearance space between the pipe to be cut and the casing or wall of the well.

Another object of my invention is to provide apparatus of the class described which is operative in cutting pipe having outwardly projecting collars or couplings at any desired location between the collars or couplings.

Another object of my invention is the provision of such apparatus which is operative to cut pipe having no projecting collars or couplings, but having an outer surface which is smooth or free from sharply projecting collars or couplings.

Still another object of my invention is the provision of a device for cutting pipe having means for retaining the cutting element or cutting elements in retracted position out of contact with the pipe to be cut until the tool has reached the desired locus of cutting and means for returning the cutting element or cutting elements to retracted position at any time during the cutting operation or when the cutting operation is completed, and retaining such element or elements in such position during withdrawal of the device from the well.

Another object of my invention is the provision of a cutting tool of the class described having means for automatically maintaining the pressure of contact of the cutting element or cutting elements with the pipe being cut at a predetermined value.

More specifically, it is an object of my invention to provide a tool for cutting an object from the outside thereof in which the radial movement of the cutting element or cutting elements during the cutting operation is in response to relative circumferential or rotational movement of the ends of a link or links carrying such element or elements which varies the length of the chord or chords represented by the projection of such links upon a plane normal to the axis of the member being cut.

Further objects of my invention include the

provision of a tool capable of performing the objects hereinbefore stated and others which will be hereinafter apparent, which tool is simple and inexpensive in construction and positive in operation.

A description of one embodiment of my invention capable of performing these objects and providing these advantages is contained in the following specification, which may be better understood by reference to the accompanying drawings in which

Fig. 1 is a side elevational view of the tool of my invention positioned in an oil well, within a casing, and around the drill pipe, the tool being in retracted or non-cutting position;

Fig. 2 is a sectional view of the tool illustrated in Fig. 1, the casing being omitted;

Fig. 3 is a vertical sectional view of the tool illustrated in Fig. 2, the tool being in operative or cutting position;

Figs. 4 to 7, inclusive, are horizontal sectional views taken on the lines 4—4, 5—5, 6—6 and 7—7, respectively, of Fig. 2;

Fig. 8 is a fragmentary plan view of the cutting element at the beginning of the cutting operation;

Fig. 9 is a fragmentary plan view of the cutting element at the end of the cutting operation;

Fig. 10 is a fragmentary vertical sectional view as taken on the line 10—10 of Fig. 9;

Fig. 11 is a view showing the control slot projected onto a vertical plane; and

Fig. 12 is a side elevational view of an embodiment of the tool of my invention for cutting off a cylindrical member from the inside thereof, the tool being illustrated in its non-cutting position;

Fig. 13 is a vertical sectional view of the embodiment illustrated in Fig. 12, the tool being illustrated with the parts in their cutting positions; and

Figs. 14 and 15 are sectional views taken as indicated by the lines 14—14 and 15—15 of Fig. 12, respectively.

Referring to the drawings, which are for illustrative purposes only, the numeral 11 indicates a casing within an oil well, and the numeral 12 indicates a string of drill pipe within the casing 11. 13 indicates generally the tool of my invention, which is secured to a string of tubing 14 in any suitable manner as by a coupling 15. The tool 13 includes a cylindrical member 16 and a chisel member or shoe 17 threadedly secured to the lower end thereof and provided with an inner outwardly diverging cutting surface 18, facilitating the introduction of the tool 13 into the

well between the drilling string 12 and the casing 11. A plurality of links 19, illustrated in the drawings as three in number, are mounted in the cylindrical member 16, so that the ends of each of the links are capable of relative circumferential or rotational movement to a limited degree. This mounting includes a bearing member 20 substantially hemispherical in shape connected by an extension 21 to the upper end of each of the links 19 and mounted for rotational movement in a bearing cavity 22 formed in the outer surface of the coupling.

The coupling 15 is provided with an opening for the reception of the cylindrical connection 21 and a cavity 23 on its inner surface around the cylindrical opening, the opening being larger than the connection 21 to permit the connection 21 to move relative to the coupling 15, as will be later described. Each of the links 19 includes an upper portion 24 adapted to engage the inner surface of the coupling 15, a central portion 25 offset radially outwardly from the upper portion 24, and a lower portion 26 in the plane of the upper portion 24. At the lower end of the lower portion 26 of each of the links 19 there is provided a semi-spherical bearing member 27 and cylindrical connection 28 between such bearing member and the link 19 similar to the bearing member 22 and connection 21 previously described.

The numeral 29 indicates a sleeve rotatively disposed within the cylindrical member 16. Secured to the inner surface of the lower end of the sleeve 29, as by rivets 30, are inwardly belled overshot or yieldable arms 31, illustrated in the drawings as three in number. The lower ends of the arms 31 are secured, as by rivets 32, to a collar 33 slidable within the cylindrical member 16. The yieldable arms 31 are bent inwardly and formed of resilient metal, so that they resiliently engage the outer surface of the drill pipe 12 and resist relative vertical and rotational movement of the sleeve 29 and the drill pipe 12.

Each of the links 19 is provided intermediate its ends with a cutting element 34, best illustrated in Figs. 5, 8, 9, and 10. As shown in Fig. 5, each of the cutting elements 34 includes a cutting surface 35 projecting slightly from the body of the cutting element upwardly and circumferentially in a clockwise direction, as viewed from above.

The sleeve 29 is provided with vertical slots 37 for the reception of the bearing members 27 and the connections 28 of the links 19, these slots being wider than the connections 28 so that the connections may move relative to the sleeve 29. The sleeve 29 is also provided with a pin 38 adapted for movement in a portion 39 of a control slot 40 in the cylindrical member 16. The length of the circumferential control slot 40 is predetermined in order to control the length of the radial movement of the cutting elements 34, as herein-after described.

In the use of the tool 13 it is lowered with the tubing string 14 around the drill pipe 12 and within the casing string 11 to the locus where it is desired to cut the drill pipe 12. During the descent of the tool 13, the string of tubing 14 may be rotated in a clockwise direction, looking downwardly, and the cutting surface 35 of the chisel member 17 pushes aside the rotary mud and any deposit between the drill string 12 and the casing string 11 and facilitates the lowering of the tool 13. If the drill string 12 is provided with outwardly projecting collars or couplings, the yieldable arms 31 are deformed outwardly during the descent of the tool, and these arms resiliently en-

gage the pipe string 12 between such collars or couplings. During such descent of the tool, the pin 38 upon the sleeve 29 is retained at the upper end of the vertical slot 39 of the cylindrical member 16 by the resistance to downward movement of the sleeve 29 caused by the resilient engagement of the arms 31 connected thereto with the pipe string 12, thus preventing the rotation of the sleeve 29 relative to the cylindrical member 16 and the movement of the cutting elements 34 to cutting position.

When the tool 13 has reached the level at which it is desired to sever the drill pipe 12, the lowering operation is terminated, and the tubing string 14 and attached cylindrical member 16 are elevated, while the sleeve 29 is retained stationary by virtue of the engagement of the arms 31 with the string of drill pipe 12, so that the pin 38 is moved from the vertical slot 39 into the circumferential slot 40 of the cylindrical member 16. During continued rotation of the tubing string 14 and the cylindrical member 16, the resilient engagement of the arms 31 with the drill pipe 12 resists rotational movement of the sleeve 29 and the lower ends of the links 19. The limit of circumferential movement of the upper ends of the links 19 relative to the lower ends of the links, as defined by the length of the circumferential slot 40 in the cylindrical member 16 and the resistance to rotation of the lower ends of the links 19 afforded by the contact of the resilient arms 31 with the drill pipe 12 and the resilience or deformability of the links 19 are so related that, when the pin 38 reaches the end of the circumferential slot 40 during rotation of the tubing string 14 and the cylindrical member 16, the cutting elements 34 are urged into contact with the drill pipe 12 with the desired degree of pressure. This pressural contact is accomplished by the relative circumferential or rotational displacement of the upper ends of the links 19 relative to the lower ends of these links, thus varying the length of the chord represented by the projection onto a horizontal plane of each of the links 19.

Continued rotation of the tubing string 14 and the cylindrical member 16 causes the cutting elements 34 to exert a cutting action upon the drill pipe 12. The upper end of the tubing string 14 being held against vertical movement, the radial advancement of the cutting elements 34 causes them to move upwardly to a slight extent, and the upward slant of the cutting surface 35 of each of the cutting elements 34 causes each cutting element to follow through this upward movement and prevents binding of the cutting elements 34 with the cut edges of the drill pipe 12. Each of the cutting elements 34 is made of a radial length greater than the drill pipe to be cut, so that the drill pipe may be completely severed. When the drill pipe is cut through, the cut-off upper portion may be removed by pulling upwardly upon the tubing string 14 with or without clockwise rotational movement of the string.

A short vertical slot 39a may be formed in the cylindrical member 16 at that end of the circumferential control slot 40 opposite the vertical slot 39 and extending downwardly therefrom. When the tool 13 is actuated so that the cutting elements 34 are in their maximum cutting position and the pipe string 12 is severed and the tool moved upwardly in the well, the pin 38 is moved to the bottom of the short vertical slot 39a, relative rotation of the ends of the links 19 is prevented, and the cutting elements 34 are

retained in their innermost position, where they support the cut-off portion of the drill pipe 12 and permit its elevation to the surface of the ground.

If desired, the tubing string 14 may be rotated in a counter-clockwise direction (as viewed from above) and lowered until the pin 38 of the sleeve 29 has been moved to a position opposite the vertical slot 39 of the cylindrical member 16, whereupon upward movement of the tubing string 14 will accomplish the withdrawal of the tool 13, the links 19 and their associated cutting elements 34 being retained in inoperative or non-cutting position by virtue of the retention of the pin 38 at the upper end of the vertical slot 39 of the cylindrical member 16 by the resistance to upward movement afforded by contact of the yieldable arms 31 with the drill pipe 12.

If the latter operation is performed, the cut-off section of the drill pipe may be removed by subsequently lowering an overshot or spear or other suitable pipe engaging mechanism into retaining engagement with the cut-off section of the drill pipe and subsequently elevating such tool and the cut-off section to the surface of the ground.

The links 19 may be formed of such width and thickness, and the openings in the coupling 15 and sleeve 29 for the reception of the extensions 21 and 28 may be made sufficiently larger than such extensions, so that, during the cutting operation of the cutting elements 34, the links are deformed circumferentially in a manner tending to wrap them around the string of drill pipe 12. With or without such deformation of the links 19, the cavities 23 and inclined faces 41 provided at the upper ends of the slots 37 on the inner surface of the sleeve 29 facilitate the relative rotational or circumferential movement of the upper and lower ends of each of the links 19, so that they assume, during the cutting operation, positions of progressively greater chords as projected upon a plane normal to the axis of the string of drill pipe 12 being severed.

If it is desired to utilize my invention in the form adapted for cutting off drill pipe from the inside thereof, it is necessary only to modify that embodiment herein described, so that, as illustrated in Figs. 12 to 15, inclusive, links 51 are in position in which their projections upon a plane normal to the pipe to be cut are of maximum length during the movement of the tool to the desired locus of cutting, at which locus relative rotation of the ends of the links 51 will cause movement of cutting elements 52 carried on the outer surface of such links in a radially outward direction into operative or cutting position with the inner surface 53 of the pipe 54 to be cut.

Since the embodiment of my invention hereinbefore illustrated and described depends for the radial movement of the cutting elements during the cutting operation upon the relative circumferential or rotational movement of the ends of the links 19, which in the inoperative or non-cutting position are parallel to the axis of the pipe being cut, it will be apparent that I have provided a cutting-off tool capable of performing its intended operation in a clearance space of very small radial dimension between the pipe to be cut and the casing or the wall of the well surrounding it, and that the tool of my invention may be employed to cut drill pipe having outwardly projecting collars or couplings anywhere between said collars or couplings, and that it may be employed to cut at any desired locus drill pipe

having no such outwardly projecting collars or couplings, since it is in no way dependent upon such collars or couplings for either its actuation into operative position or the performance of its cutting operation.

It will be obvious also from the foregoing that the tool of my invention accomplishes the object primarily stated of providing means for retaining the cutting elements in retractive or inoperative position during the descent of the tool and during removal of the tool either before or after the pipe has been severed.

Likewise it will be seen that by controlling the rate of the cutting operation by the resistance to deformation of the links 19, the resistance to rotation of the yieldable arms 31 engaging the drill pipe 12 and the circumferential length of the slot 40 in the cylindrical member 16, I have provided a tool including means by automatically and in a predetermined manner fixing the rate of pressural contact of the cutting elements 34 with the drill pipe 12, and hence the rate of the cutting action.

While that embodiment of my invention hereinbefore illustrated and described is fully capable of performing the objects and providing the advantages primarily stated, there are various other embodiments of my invention likewise capable of performing these objects and providing such advantages. Likewise, embodiments of my invention are capable of uses differing from those hereinbefore illustrated and described. I therefore wish my invention to be understood as not restricted to such embodiments or uses, but entitled to the full scope of the claims which follow.

I claim as my invention:

1. A cutting-off stool, including: a body member; a link so mounted in said body member that its ends are adapted for relative rotational movement on rotation of said body member; a cutting element carried by said link and movable into the member to be cut in response to such relative rotational movement; and releasable means adapted for restraining such rotational movement.

2. A cutting-off tool, including: a body member; a link so mounted in said body member that its ends are adapted for relative rotational movement on rotation of said body member; a cutting element carried by said link and movable into the member to be cut in response to such relative rotational movement; and means adapted for restraining such rotational movement during movement of said body member in one direction relative to the member to be cut, said means being releasable by movement of said body member in the opposite direction.

3. A cutting-off tool, including: a body member; a link so mounted in said body member that its ends are adapted for relative rotational movement on rotation of said body member; a cutting element carried by said link and movable into the member to be cut in response to such relative rotational movement; means adapted for retaining said cutting element out of contact with the member to be cut during movement of the body member in one direction relative thereto, said means being releasable by movement of the body member in the opposite direction; and means adapted for retaining said cutting element in contact with the severed portion of the member to be cut, said means being responsive to the weight of such portion upon said cutting element.

4. In apparatus for cutting pipe, the combina-

tion of: a body member; a rotatable member associated with said body member; a link so connecting said members that the length of its projection upon a plane normal to the axis of the pipe is varied by the relative rotation of said members; a cutting element associated with said link and movable between retracted and cutting position in response to variation in such projected length of said link; means connected to one of said members adapted for restraining its rotation relative to the other of said members by engagement with the pipe; and means for rotating the other of said members.

5. In apparatus for cutting pipe, the combination of: a body member; a rotatable member associated with said body member; a resilient link so connecting said members that the length of its projection upon a plane normal to the axis of the pipe is varied by the relative rotation of said members; a cutting element associated with said link and movable between retracted and cutting position in response to variation in such projected length of said link; means connected to one of said members adapted for restraining its rotation relative to the other of said members by engagement with the pipe; means for rotating the other of said members; and stop means limiting the relative rotation of said members.

6. In apparatus for cutting pipe, the combination of: a body member; a rotatable member associated with said body member; a link so connecting said members that the length of its projection upon a plane normal to the axis of the pipe is varied by the relative rotation of said members; a cutting element associated with said link and movable between retracted and cutting position in response to variation in such projected length of said link; means connected to one of said members adapted for restraining its rotation relative to the other of said members by engagement with the pipe; means for rotating the other of said members; stop means limiting the relative rotation of said members; and locking means associated with said members and adapted for restraining their relative rotation during their movement in one direction axially of the pipe.

7. In apparatus for cutting pipe, the combination of: a body member; a rotatable member associated with said body member; a link so connecting said members that the length of its projection upon a plane normal to the axis of the pipe is varied by the relative rotation of said members; a cutting element associated with said link and movable between retracted and cutting position in response to variation in such projected length of said link; means connected to one of said members adapted for restraining its rotation relative to the other of said members by engagement with the pipe; means for rotating the other of said members; stop means limiting the relative rotation of said members; and locking means associated with said members and adapted for restraining their relative rotation during their movement in one direction axially of the pipe and for freeing said members for relative rotation during their movement in the opposite direction.

8. In apparatus for cutting pipe, the combination of: a body member; a rotatable member associated with said body member; a link; a plurality of means so connecting said link to said members that the length of the projection of said link upon a plane normal to the axis of the pipe is varied by the relative rotation of said

members, one of said means adapting the link and the member which it connects for relative movement axially of the pipe; a cutting element associated with said link and movable between retracted and cutting position in response to variation in such projected length of said link; means connected to one of said members adapted for restraining its rotation relative to the other of said members by engagement with the pipe; and means for rotating the other of said members.

9. A cutting tool, including: a body member; means so mounted in said body member that its ends are adapted for relative displacement substantially parallel to the surface of the member to be cut by rotation of said body member; and cutting means carried by said means and movable into the member to be cut in response to such relative displacement.

10. A cutting tool, including: a body member adapted for passing over the member to be cut; means so mounted in said body member that its ends are adapted for relative rotational movement circumferentially of the member to be cut by rotation of said body member; and a cutting element carried by said means and movable into the member to be cut in response to such relative rotational movement.

11. A cutting tool, including: a body member; a link so mounted in said body member that its ends are adapted for limited relative movement substantially parallel to the surface of the material to be cut by rotation of said body member; and a cutting element carried by said link and movable into the material to be cut in response to such relative movement.

12. A cutting tool, including: a body member; a resilient supporting member so mounted in said body member that its ends are adapted for relative rotational movement by rotation of said body member; and a cutting element carried by said supporting member and movable in a direction substantially normal to such rotational movement and into the member to be cut in response to such relative rotational movement.

13. A cutting-off tool, including: a body member; a link so mounted in said body member that its ends are adapted for limited relative rotational movement substantially parallel to the surface of the member to be cut on rotation of said body member; and a cutting element carried by said link and movable into the member to be cut in response to such relative rotational movement, the limit of such rotational movement being so related to the thickness of the member to be cut that said cutting element severs the member to be cut when or before such limit is reached.

14. A cutting tool, including: a body member; a member so mounted in said body member that its ends are adapted for limited relative rotational movement substantially parallel to the surface of the member to be cut during rotation of said body member; and a cutting element carried by said member and movable into the member to be cut in response to such relative rotational movement, said member being of such resilience as to limit the maximum pressural contact of said cutting element with the member to be cut to the desired value.

15. A cutting tool, including: a body member; a link so mounted in said body member that its ends are adapted for relative movement substantially parallel to the surface of the member to be cut; a cutting element carried by said link

and movable into the member to be cut in response to such relative rotational movement; and retarding means adapted for restraining such relative movement by engagement with the member to be cut.

16. A cutting tool, including: a body member comprising portions adapted for relative movement; a supporting member so connected to said portions that its ends are adapted for relative displacement substantially parallel to the surface of the member to be cut upon relative movement of said portions; and cutting means carried by said supporting member and movable into the member to be cut in response to such relative 15

displacement of the ends of said supporting member.

17. A cutting tool, including: a body member; a supporting member so mounted in said body member that its ends are adapted for limited relative movement substantially parallel to the surface of the member to be cut by rotation of said body member; and a cutting element carried by said supporting member and movable into the member to be cut in response to such relative movement, said cutting element being at substantially the same angle with the surface of the member to be cut as the direction of its movement into such member.

JACOB G. HEIM.

CERTIFICATE OF CORRECTION.

Patent No. 2,299,063.

October 13, 1942.

JACOB G. HEIM.

It is hereby certified that error appears in the printed specification of the above numbered patent requiring correction as follows: Page 3, first column, line 50, for "position" read --positions--; and second column, line 14-15, for "resistaance" read --resistance--; line 37, claim 1, for the word "stool" read --tool--; and that the said Letters Patent should be read with this correction therein that the same may conform to the record of the case in the Patent Office.

Signed and sealed this 22nd day of December, A. D. 1942.

Henry Van Arsdale,

Acting Commissioner of Patents.
